UNITED STATES PATENT OFFICE.

ORLANDO W. BROWN, JR., OF SANFORD, MAINE.

STEPLADDER.

1,345,990.

Specification of Letters Patent.

Patented July 6, 1920.

Application filed December 18, 1919. Serial No. 345,836.

To all whom it may concern:

Be it known that I, ORLANDO W. BROWN, Jr., a citizen of the United States, and a resident of Sanford, in the county of York 5 and State of Maine, have invented a new and Improved Stepladder, of which the following is a full, clear, and exact description.

This invention relates to improvements in stepladders, an object of the invention being to provide a stepladder having rear or supporting legs which can be flared apart at their lower ends to give added support to the ladder and which will be securely held in this position.

15 A further object is to provide a collapsible or folding stepladder which is made of steel or other suitable metal, which can be conveniently folded or collapsed, and which can be secured in expanded form to 20 securely and rigidly support the ladder in operative position.

With these and other objects in view the invention consists in certain novel features of construction, and combinations and arrangements of parts as will be more fully hereinafter described and pointed out in the claims.

In the accompanying drawings—

Figure 1 is a view in rear elevation illustrating my improved stepladder in operative position, the dashed lines indicating the position of the parts when folded.

Fig. 2 is a view in side elevation;

Fig. 3 is a fragmentary plan view of the 35 upper transverse brace 18;

Fig. 4 is a view in side elevation of Fig. 3;

Fig. 5 is a view in section on the line 5—5 of Fig. 4;

Fig. 6 is a view in elevation illustrating 40 the connection of the braces of the rear legs;

Fig. 7 is a view in section on the line 7—7 of Fig. 6;

Fig. 8 is a view in section on the line 45 8—8 of Fig. 6;

Fig. 9 is an enlarged view in section on the line 9—9 of Fig. 2;

Fig. 10 is an enlarged view in section on the line 10—10 of Fig. 2;

50 Fig. 11 is a fragmentary view partly in elevation and partly in section illustrating

the rear end of one of the pivoted links and its co-operating parts; and

Fig. 12 is a view in section on the line 12—12 of Fig. 11.

1 represents the front legs of my improved stepladder. These legs are preferably composed of parallel angle bars 2 and 3 having spacing plates 4 at their lower ends and secured at their upper ends to rearwardly projecting bars 5. The legs 1, 1, are connected by horizontally positioned metal bars 6 and support steps 7 which are preferably of wood. A top step or platform 8 also preferably of wood is secured 65 upon the bars 5 and supporting or rear legs 9 are pivotally connected at their upper ends to the bars 5 and this pivotal connection is a sufficiently loose one to permit of pivotal movement of the legs and also slight 70 lateral movement of the legs to allow for the spreading of the lower ends of the legs apart, as will fully hereinafter appear. The rear legs 9 are tubular in form and longitudinally slotted with parallel webs 10 projecting 75 from the tubular portion of the legs at opposite sides of the slots therein, so that the legs form, in effect, longitudinal grooves to accommodate the parts which will be 80 hereinafter described.

A curved brace 11 consisting of two curved bars 11^a and 11^b is secured at its ends to the legs 9 and a convenient manner of connecting the members 11^a and 11^b to the legs is shown in Figs. 11 and 12. The ends of the 85 bars are bent in angular form and projected between the webs 10, 10, and secured by means of a rivet 12. The ends of the bars 11^a and 11^b constitute stops or shoulders which limit the downward pivotal movement of brace links 13. These brace links are pivotally connected at one end to the legs 1, as shown at 14, and at their rear ends are curved slightly downwardly and provided with knobs or enlargements 15 at 95 their free ends which move in the tubular portions of the legs 9 with the links extending between the webs 10. It will thus be noted that the links 13 at their enlarged ends 15 can be swung upwardly moving in 100 the tubular legs 9 when it is desired to collapse the ladder or draw the legs together,

but the downward movement of the links 13 is limited to a normal horizontal position to sustain the legs in their extended operative position.

5 A pair of oppositely positioned angular braces 16 have their respective ends secured between the webs 10 of the legs 9. The upper ends of these braces 16 are near the upper ends of the legs and the lower ends 10 of the braces are adjacent the lower ends of the legs, while the intermediate portions of the braces overlap, as clearly shown in Figs. 1 and 6, and are located in rear of the curved brace 11. The braces 16 have yokes 15 secured thereto and the two members 11^a and 11^b of the brace 11 are accommodated in these yokes 17. One of the yokes is secured to one of the bars 11^a and the other yoke to the other bar 11^b so that when the 20 legs 9 are expanded, the lateral movement of the braces 16 will cause a telescoping action of the members of the brace 11 to compensate for this movement of the legs.

A horizontal brace 18 is secured at its 25 ends to the braces 16 adjacent the upper ends of the ladder and this brace 18 also constitutes two members 18^a and 18^b with the overlapping ends of said members projected through a slotted coupling yoke 19 30 and having their extreme ends bent at an angle forming stops 20 which limit the expansion of the brace. The brace 18 also supports a pivoted platform 21 which is provided with circular openings 22 receiving 35 the brace 18, and is made with extensions 23 which engage under one of the steps to hold the platform in horizontal position yet permit the platform to be folded upwardly when not desired for use.

40 By reason of the construction above described, the lower ends of the legs 9 can be moved toward or away from each other to expand or contract the rear support formed by said legs. In other words, the 45 lower ends of the legs 9 can be moved outwardly, as shown in Fig. 1, so that the legs assume an inclined position, and the lower ends of the legs have an extended bearing which prevents lateral movement of the 50 ladder and affords an extremely secure support for a person on the ladder. When the legs are moved toward each other to contract the ladder, this movement is compensated for by the braces 11 and 18 with their 55 telescoping or sliding members, and the outward movement of the legs is limited by the shoulders 20 of the brace 18 and would also be limited by the engagement of the intermediate portions of the braces 16 with each 60 other as the yokes 17 on these braces are in the same horizontal plane and would cause a binding action of the braces 16 against each other to limit the spreading movement of the legs.

65 Various slight changes may be made in

the general form and arrangement of parts described without departing from the invention, and hence I do not limit myself to the precise details set forth, but consider myself at liberty to make such changes and 70 alterations as fairly fall within the spirit and scope of the appended claims.

I claim:

1. A stepladder, comprising front legs, 75 steps on the front legs, rearwardly projecting bars secured to the upper ends of the front legs, rear legs pivotally connected to the bars, means connecting the rear legs and permitting lateral movement of the lower ends of the legs, said rear legs of tubular 80 longitudinally slotted formation, links pivotally connected to the front legs, and enlargements on the ends of the links movable in the tubular rear legs.

2. A stepladder, comprising front legs, 85 steps on the front legs, rearwardly projecting bars secured to the upper ends of the front legs, rear legs pivotally connected to the bars, sliding braces connecting the rear legs and permitting lateral movement of the 90 lower ends of the rear legs, said rear legs of tubular longitudinally slotted formation, links pivotally connected to the front legs, enlargements on the ends of the links movable in the tubular rear legs, and means for 95 limiting the downward movement of the links in the rear legs.

3. A stepladder, comprising front legs, 100 steps on the front legs, rearwardly projecting bars secured to the upper ends of the front legs, rear legs pivotally connected to the bars, angular braces secured at their ends to the rear legs and at their intermediate portions overlapping each other, a brace bar comprising two sections, the respective sections secured to the rear legs, and the intermediate portions of said first-mentioned braces secured respectively to the members of the last-mentioned brace bar.

4. A stepladder, comprising front legs, 11 steps on the front legs, rearwardly projecting bars secured to the upper ends of the front legs, rear legs pivotally connected to the bars, angular braces secured at their ends to the rear legs and at their intermediate portions overlapping, a curved brace bar consisting of two members, the respective members secured to the legs and to the intermediate portions of the first-mentioned brace bars, a second brace bar connecting 12 the first-mentioned braces and consisting of two members, and a yoke connecting the last-mentioned members and limiting their sliding movement relative to each other.

5. A stepladder, comprising front legs, 12 steps on the front legs, rearwardly projecting bars secured to the upper ends of the front legs, rear legs pivotally connected to the bars, angular braces secured at their ends to the rear legs and at their intermediate portions overlapping, a curved brace bar consisting of two members, the respective members secured to the legs and to the intermediate portions of the first-mentioned brace bars, a second brace bar connecting 12 the first-mentioned braces and consisting of two members, and a yoke connecting the last-mentioned members and limiting their sliding movement relative to each other.

diate portions overlapping, a curved brace bar consisting of two members, the respective members secured to the legs and to the intermediate portions of the first-mentioned 5 brace bars, a second brace bar connecting the first-mentioned braces and consisting of two members, a yoke connecting the last-men-

tioned members and limiting their sliding movement relative to each other, a platform pivotally supported on said last-mentioned 10 brace bars, and extensions on the platform adapted to engage a step to support the platform in horizontal position.

ORLANDO W. BROWN, JR.
